UNITED STATES PATENT OFFICE.

PETER P. RUSS, OF ORG, MINNESOTA.

DESIGN FOR A SEPARATOR.

SPECIFICATION forming part of Design No. 30,789, dated May 16, 1899.

Application filed April 13, 1899. Serial No. 712,934. Term of patent 14 years.

To all whom it may concern:

Be it known that I, PETER P. RUSS, a citizen of the United States, residing at Org, in the county of Nobles and State of Minnesota, have invented and produced a certain new and original Design for Separators; and I do declare the following to be a full, clear, and exact description of the invention, such as will enable others skilled in the art to which it appertains to make and use the same.

The invention relates to a new and original design for a separator; and it consists of a separator of the configuration shown in the accompanying drawings, in which—

Figure 1 is a plan view, and Fig. 2 is an edge view.

The leading feature of the design comprises a flat horizontal bar 1 and a series of flat fingers 2 projecting from the rear edge of said

bar and across its forward edge and occupying a plane above that of the bar and provided on each side with abrupt angular shoulders 5, which successively increase in breadth from their outer ends to the forward edge of the bar, said fingers projecting from the bar at right angles thereto and arranged between the two ends of the bar.

Having thus described my invention, what I claim is—

The design for a separator, as herein shown and described.

In testimony whereof I have hereunto set my hand in presence of two subscribing witnesses.

PETER P. RUSS.
